(57) **CLAIM**

The ornamental design for a aerosol dispenser, as shown and described.

DESCRIPTION

FIG. 1 is a perspective view from above and to one side of the dispenser showing the new design.

FIG. 2 is a front view of the aerosol dispenser of FIG. 1.

FIG. 3 is a rear view of the aerosol dispenser of FIG. 1. FIG. 4 is a right side view of the aerosol dispenser of FIG. 1, the left side view being a mirror image thereof; FIG. 5 is a top plan view of the aerosol dispenser of FIG. 1; and,

FIG. 6 is a bottom view of the aerosol dispenser of FIG. 1. The broken line showing is for illustrative purposes only and forms no part of the claimed design.
